(57) **CLAIM**

I claim the ornamental design for an adjustable desk stand,
as shown and described.

DESCRIPTION

FIG. 1 is a perspective view of an adjustable desk stand,
showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view of an adjustable desk stand
shown in an environment of use.

In FIG. 8, the broken lines depicting a table top are representing
environmental subject matter that forms no part of the
claimed design. All other broken lines are depicting
portions of the article that form no part of the claimed
design.

1 Claim, 8 Drawing Sheets
